PRESSBOARD FOR VELVET, ETC.

Rubin Bass, Brooklyn, N. Y., assignor to American
Plush & Velvet Pressboard Co. Inc., New York,
N. Y., a corporation of New York

Application February 8, 1938, Serial No. 189,365

5 Claims. (Cl. 38—140)

My invention relates to improvements in what are commonly called pressboards used for pressing velvet, velours and other nap or pile fabrics such as set forth in my former Patents Nos. Re. 5 16,194 and 1,485,825.

These devices comprise multiply woven textile fabric foundations having wire pins secured therein. These wires are usually of steel and frequently rust out under the alternate steaming 10 and drying to which they are subjected in use. The pins are frequently displaced when pressure is applied unless a suitable support is provided such as a wire meshwork stitched to the cloth foundation. This is satisfactory for many cases 15 but the stitching is expensive if done properly. If not done properly, the stitching displaces the pins so as to leave a pattern of the displaced pins on the fabric which is pressed on the board. This stitching also sometimes rots or rusts out 20 or is otherwise destroyed.

I also sometimes employ tubular members to permit the passage of steam through the foundation and it is difficult to hold them in place.

After many years of experimentation and study 25 I have discovered that these difficulties may be solved by securing the wire loops of adjacent pins together at the back of the cloth foundation by soldering, brazing or welding.

Figure 1 is an enlarged fragmentary section 30 of a pressboard embodying one form of my invention.

Figure 2 is a view of the back of the same device, parts being broken away.

Figure 3 is a view of the back of a modified 35 form of my invention.

Figure 4 is a sectional view showing the connecting metal being sprayed on.

The foundation 7 is usually formed of a number 40 of layers of woven cotton duck stitched or cemented together. The points of the pins 8 are inserted through the foundation leaving the loop portions 9 at the back and resting against the surface of the rearmost layer. They are usually arranged along inclined lines as shown 45 in Fig. 2. The eyelets or tubular members 10 are inserted from the back between rows of pins leaving their flanges at the back. A fine mesh wire 11 may be applied to the back to hold the pins and tubes in place.

The anchorage of the pins may be effected in several ways. For instance by applying solder 50 55 55 along the lines of the pin loops connecting said loops. This not only reinforces the pins and holds them in place but coats them so that

there is no danger of their rusting where the solder is applied.

The wire mesh may be soldered, brazed or welded to the backs of the pins so as to hold them securely in place. 5

A suitable paint or coating compound 13 may be applied to the foundation between the rows 12—12 and impregnate the fabric at the roots of the pins so as to assist in preventing corrosion or rusting of the wires. The fabric may be 10 suitably impregnated with the protective compound before or after the pins are inserted.

In place of the strips of solder 12, I may apply a layer 14 of solder as indicated in Fig. 3.

A metallic film or layer may be applied to the 15 backs of the pins by means of a hot spray 15 so as to permanently connect the wires. In all cases, the fabric is flexible and the pins are held permanently in place with a minimum susceptibility to rust or corrosion. 20

The spray may be applied directly to the back 25 of the cloth and the loops of the pins or if wire meshwork is employed the spray may be applied to it in which case part of the spray will pass through the meshwork and unite the pins and the meshwork. 25

A suitable so-called liquid solder or cold solder or metallic paint or cement may be applied to the back of the board either directly to the cloth and the loops of the wire and also to the eyelets 30 (if used) or it may be applied against the wire meshwork (if used) in which latter case the liquid will penetrate the meshwork and bind the pins to each other and to the wire meshwork. 30

I claim:

1. A pressing device comprising a cloth foundation having U-shaped needles, the points of said needles projecting from one face of said foundation and the loop portions resting exposed on the opposite face thereof, a layer of 40 wire mesh covering said loop portions and opposite face of the foundation and a coating of solder over said wire mesh whereby said wire mesh and loop portions are connected to prevent displacement of the needles. 45

2. A pressing device comprising a cloth foundation having tubular fluid flow members passing therethrough and having U-shaped needles, the points of said needles projecting from one face of said foundation and the loop portions 50 resting on the opposite face thereof, the tubular members being located at intervals throughout the entire area of the device, and a connection of solder between the loop portions of the needles and the tubular members to prevent the 55

needles and tubular members from working loose.

3. A flexible pressing device comprising a cloth foundation having U-shaped needles, the points of said needles projecting from one face of said foundation and the loop portions resting directly against the opposite face thereof, a layer of wire mesh covering said loop portions and said opposite face of the foundation and a thin layer of solder penetrating the wire mesh and connecting said wire mesh directly to the loop portions to prevent displacement of the needles.

4. A pressing device comprising a cloth foundation having U-shaped needles arranged in rows, the points of said needles projecting from one face of said foundation and the loop portions resting against the opposite face thereof, a layer of wire mesh covering said loop portions and said opposite face of the foundation and thin strips of solder following the rows of the needles over-

lying and penetrating the wire mesh at intervals and connecting said loop portions to the wire mesh to prevent displacement of the needles, adjacent strips being spaced from each other.

5. A pressing device comprising a cloth foundation having U-shaped needles arranged in spaced parallel rows, the points of said needles projecting from one face of said foundation and the loop portions resting against the opposite face thereof, a layer of wire mesh covering said loop portions and said opposite face of the foundation, thin strips of solder following the rows of needles in their parallel and spaced relationship connecting said wire mesh and loop portions to prevent displacement of the needles and spaced tubular fluid flow members in spaces between the parallel strips and extending through the foundation.

RUBIN BASS.
